(57) **CLAIM**

The ornamental design for a water spray swimming pool, as shown and described.

DESCRIPTION

FIG. 1 is a top perspective view of a water spray swimming pool, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a detail view of area 9 in FIG. 1.

The dash-dot broken lines depict the bounds of the detail view and form no part of the claimed design.
